CLAIM

The ornamental design for a container for multiple compact discs, as shown and described.

DESCRIPTION

FIG. 1 is a front elevational view of a container for multiple compact discs showing our new design; FIG. 2 is a right side elevational view thereof; FIG. 3 is a rear elevational view thereof; FIG. 4 is a left side elevational view thereof; FIG. 5 is a top plan view thereof; FIG. 6 is a bottom plan view thereof; and FIG. 7 is a perspective view thereof, shown in use; the broken line showing a compact disc being for illustrative purposes only and forming no part of the claimed design.

FIG. 1

FIG. 2

FIG. 3

FIG. 4

FIG. 5

FIG. 6

FIG. 7
